CLAIM

The ornamental design for a light fixture, as shown and described.

DESCRIPTION

FIG. 1 is a perspective view of a light fixture embodying the design of the present invention;

FIG. 2 is a front side elevational view of the light fixture illustrated in FIG. 1;

FIG. 3 is a right side elevational view of the light fixture illustrated in FIG. 1;

FIG. 4 is a left side elevational view of the light fixture illustrated in FIG. 1;

FIG. 5 is a top plan view of the light fixture illustrated in FIG. 1; and,

FIG. 6 is a bottom plan view of the light fixture illustrated in FIG. 1.

The broken lines in the drawings depict portions of the light fixture that form no part of the claimed design.
